GARMENT FORM RETAINER

Frank Y. Sherbondy, P.O. Box 7021, San Antonio, Tex.

Filed Dec. 21, 1959, Ser. No. 860,931

1 Claim. (Cl. 223—71)

This invention relates to garment form retaining devices for use with garments having overlapping front panels. More particularly, this invention is an improvement upon the garment form retaining device which is the subject of my United States Patent No. 2,641,390 issued June 9, 1953.

Garment form retaining devices of the type presented in the above-cited patent are adapted to hold the overlapping front panels of a coat in a position where one panel is over the other when the coat is placed on a hanger so as to prevent sagging and deformation of the coat. The garment form retaining devices each comprise a long flat body for insertion between the overlapping front portions of the garment. An elongate flap is connected intermediate one longitudinal edge thereof to the body adjacent to, and inwardly from, one end of the body. The flap extends lengthwise of the body and is outwardly swingable with respect to the body for engagement through a button hole in one garment portion. A slot is provided in the body for coupling the body with a button on the other portion of the garment.

Preferably the flap is cut or punched from the body so that the connection remains integral with the body intermediate the ends of the flap. When the flap is passed through the button hole, the connection extends through the button hole such that the body is adjacent one side of the garment material and the flap is adjacent the other side of the garment material.

Such garment form retaining device has proved very satisfactory in use. However, variations in length of the button hole affect efficient utilization of the device.

Accordingly, the primary object of the present invention is to provide an improved garment form retaining device of the above-described type which incorporates means for adjusting the length of the connection between the flap and the body, whereby the same device can be efficiently utilized with garments having button holes of varying lengths.

A further object of the invention is to provide a garment form retaining device of the type described incorporating means for adjusting the length of the connection as prescribed above, which device can be economically manufactured as a unitary structure.

Still a further object of this invention is to provide a garment form retainer in accordance with the above objects which assures proper positioning of the garment form retaining device at all times, and which facilitates attachment of the device to the garment.

In order to achieve the aforesigned objects, the invention provides for perforating the body of the retainer form along the swinging axis of the elongated integral flap carried by the body and adapted to engage a button hole on the garment.

The invention will be better understood after considering the following detailed description of the invention which refers to the annexed drawings.

In the drawings:

2

Figure 1 is a perspective view of the garment form retainer provided by this invention;

Figure 2 is a front elevational view of a garment having operatively positioned thereon the garment form retainer shown in Figure 1; and

Figure 3 is a detailed perspective view of the end of the retainer shown in Figure 1 which has integrally connected thereto the flap adapted to extend through button holes of varying lengths.

10 Referring more particularly to Figure 1, the numeral 2 designates a garment form retainer constructed in accordance with the present invention. The retainer 2 is formed from an elongated flat body, plate or card 4 which is made of any suitable yieldable but relatively 15 stiff material such as cardboard, flexible plastic, or the like. The body 4 is cut along the line 6 whereby an elongated flap 8 is formed. As shown in Figure 3, such flap 8 is swingable outwardly from the body 4 along an axis 10 defined by the integral connection 12 between the flap 8 and body 4. The body is provided 20 with perforations 14 which are disposed along the axis 10 so that the length of the connection between flap 8 and body 4 can be adjusted merely by tearing the connections 15 between cut 6 and the perforations.

25 The body 4 is also provided with a longitudinal slot 16 having an enlarged opening 18 through which a button can be easily inserted as hereinafter explained. Opposite faces of slot 16 abut one another, on either side of the enlargement 18.

30 From the foregoing discussion, it should be apparent that the garment form retainer 2 can be manufactured by merely cutting the body 4 along line 6 and the defining boundaries of slot 16, and perforating the body partially along the axis 10 between confronting terminal 35 edges of line 6.

The manner in which the invention is applied to a garment is illustrated in Figure 2 wherein a typical coat 20 is shown having overlapping front portions 22 and 24. Button holes 26, 26¹ are disposed adjacent the 40 longitudinal edge 23 of portion 22, and buttons 28, 28¹ are attached to portion 24 by any suitable means such as by thread, or the like.

Obviously, buttons 28, 28¹ are positioned to cooperate with button holes 26 and 26¹ respectively when the garment 45 is secured on an individual. However, when the form retainer 2 provided by this invention is utilized, one button and the associated button hole cooperate with the retainer as explained below.

When the invention is applied to the garment of Figure 2, the retainer 2 is placed between the overlapping portions 22 and 24 and the flap 8 is passed through the button hole 26¹ as shown. The length of the connection 12 can be adjusted by tearing free either one or 50 both of the perforations 14 shown, so as to make the connection of a length corresponding to the length of the button hole, and so as to facilitate passage of flap 8 through the button hole.

After the flap 8 is passed through the button hole, the button 28 is passed through enlargement 18 and the 55 button is pulled forward in slot 16 to the position shown in Figure 2. The abutting edges of the slot 16 engage the thread securing the button to the garment and hold the retainer in position so that the portion 22 of coat 20 overlaps portion 24 thereof.

60 The provision of perforations along axis 10 of the connection 12 between flap 8 and body 4 ensures straight tearing of the connection in addition to providing a means of adjusting the length of the connection. This is particularly important because if such connection is 65 not torn straight, the retainer will not position itself horizontally so as to maintain the proper alignment of overlapping portions 22 and 24.

It is important to note that perforations 14 are not provided across the entire connection 12 but are only provided across part of such connection. This ensures rigid coupling of flap 8 to the body 4, and allows for adjustment of length of the connection without accidental disconnection of the flap entirely from the body.

It is also important to understand that the body 4 is made from a material which is sufficiently stiff to properly hold the garment as explained above, and yet sufficiently yieldable (a) to allow for the swinging of flap from the body of the material, and (b) to allow for some bending of flap 8, if necessary, to pass that flap through the button hole.

From the foregoing discussion, it should be apparent that the objects of the invention have been successfully achieved. Accordingly, I claim:

A form retainer for a coat garment, said garment having overlapping front portions with at least one button hole on one portion, and at least one button on the other portion, said retainer comprising an elongated flat body of yieldable material for insertion between the overlapping front portions of the garment, said body being cut whereby an elongate flap is coupled to said

body by a connection integral with said flap and said body, said flap being swingable outwardly from said body about an axis defined by said connection, said body having perforations extending from one end of said coupling along said axis to a point spaced from the other end of said coupling whereby the length of said connection is adjustable by severing the portions of said body between said cut and said perforations, said flap being positioned inwardly of an end of said body and adapted for engagement in said button hole, said body also having a longitudinal slot with an axis parallel to said axis defined by said connection, said slot having one end spaced from said flap and the other end spaced from the other end of said body, said slot having an enlarged opening therein spaced from said one end of said slot to facilitate passing a button through said body, said slot having side edges of said body in engagement therealong on either side of said enlarged opening.
